ELECTRIC SIGNALING OR INDICATING
MEANSHenry Thomas Ringrose, West Park, Leeds,
EnglandApplication January 12, 1935, Serial No. 1,558
In Great Britain January 29, 1934

4 Claims. (Cl. 177—311)

This invention relates to electric signaling or indicating means as applied to apparatus for indicating the presence of inflammable vapours or gases, and of the kind wherein a lamp, constituting a warning lamp has its circuit completed by a vacuum operated switch or collapsible diaphragm when a predetermined vacuum is created by combustion upon an incandescent filament in a porous vessel of inflammable vapours or gases which diffuse therewith or are aspirated thereto.

In this kind of apparatus it has been proposed to provide a smaller capacity lamp in series with the warning lamp and which functions under normal conditions, said smaller capacity lamp being short-circuited by the vacuum operated switch or collapsible diaphragm when the warning lamp circuit is completed thereby as a result of the predetermined vacuum being attained in the porous vessel.

According to the invention the warning lamp has associated therewith a relay adapted to be energized when the warning lamp circuit is completed by the vacuum operated switch or collapsible diaphragm and to maintain said lamp-circuit irrespective of the subsequent operation or action of the vacuum operated switch or collapsible diaphragm. Preferably also a manually operated switch would be provided in the relay circuit whereby, once the warning lamp circuit has been completed by the vacuum operated switch or collapsible diaphragm, the relay circuit can be broken from time to time so as to ascertain whether the predetermined vacuum exists in the porous vessel and the lamp circuit is still completed through the vacuum controlled or collapsible diaphragm. Thus if the lamp is not put out when the relay circuit is broken, the lamp circuit must still be made through the vacuum controlled switch or collapsible diaphragm. On the other hand if the lamp is extinguished when the relay circuit is broken, this indicates that the vacuum switch or collapsible diaphragm has previously operated to break the lamp circuit and that the vacuum has been destroyed.

Should the filament in the porous vessel be burnt out in use as a result of an excess of vapour or gas or as the result of a defect there will be a rapid cooling in the porous vessel and in consequence a vacuum will be set up to cause the warning lamp circuit to be completed through the vacuum operated switch or collapsible diaphragm. The porous vessel would preferably have a transparent portion whereby the filament therein can be inspected when the warning lamp

operates, to first ascertain that said filament is functioning. If it is functioning then the presence of at least the predetermined percentage of inflammable vapour or gas is indicated by the warning lamp.

In order that the invention may be clearly understood and readily carried into effect, the same will now be more fully described with reference to and by the aid of the accompanying drawings, wherein:—

Figure 1 is a part sectional side elevation of the lamp head or top of an apparatus, in the form of a miner's lamp, for indicating or recording the presence of inflammable vapours or gases in mines.

Figure 2 is a plan of Figure 1.

Figure 3 is a side elevation taken at right angles to Figure 1 and in the direction of the arrow A, the outer cover or cap and lamp glass being omitted for the sake of clearness.

Figure 4 is another elevation of Figure 1, but taken in the direction of the arrow B.

Figure 5 is an electrical circuit diagram of the apparatus.

Referring to the drawings, the metal base plate 1 of the lamp head or top which is connected to the positive terminal of the battery or accumulator (not shown) has mounted upon insulating blocks 2 thereon, a pair of lamp holders 3, 4, the former of which carries a lamp 5 and the other a warning lamp 6 of larger capacity. The positive terminal 7 of the lamp holder 3 is connected to the base plate or top 1 by means of a lead 8 and screw-down terminal 9, and the negative terminal 10 of said lamp holder 3 is connected by a lead 11 to the positive terminal 12 of the other lamp holder 4 whose negative terminal strip 13 is connected to a binding post 14 passing through an insulating bush 15 in the base or top 1 to the negative terminal of the accumulator or battery (not shown). Thus the lamps 5 and 6 are connected in series and their relative capacities are such that the lamp 5 normally glows, whilst the filament of the other lamp 6 normally passes current without becoming incandescent.

The positive terminal 12 of the lamp holder 4 is connected by a lead 16 to a bracket 17 which is mounted upon an insulating plate 18 on the base or top 1 and secured to the latter by means of screws 19 passed through insulating washers 20, the said bracket 17 being thereby insulated from the said base or top 1. The bracket 17 carries a spring arm 21 having a contact 22 adapted to be engaged by another contact 23 carried by a diaphragm 24 when the lat-

ter collapses to a predetermined amount. This hollow metal diaphragm is connected electrically by a metal tube 25 and hollow pillar 26 to the base or top 1, whilst the passage 27, afforded from 5 the interior of the diaphragm 24 by the tube 25 and hollow pillar 26, communicates directly with a porous vessel 28 in which a vacuum is created 10 in accordance with the percentage of inflammable vapours or gases in the surrounding atmosphere. The contact 23 passes through a hole 15 in the spring arm 21 and the latter is adapted to be adjusted to vary the gap between the contacts 22 and 23 in accordance with warning signal requirements.

15 A relay, indicated by coils 29, is connected across the larger capacity lamp 6, and the vacuum operated switch or collapsible diaphragm 24 is connected across the smaller capacity lamp 5, whilst the armature 30 of the relay is connected through a make and break switch to the positive side of the smaller capacity lamp 5 and associated vacuum controlled switch or collapsible diaphragm 24. Thus as shown the relay is mounted upon an insulating platform 31 fixed 20 on the pillar 26 and the armature 30 has a strip contact 32 which is normally engaged by a pin 33 of a spring-loaded switch plunger 34 working in a barrel afforded by said pillar 26, said plunger 34 having an insulating cap 35 which is engaged by a spring-loaded press-button plunger 36 mounted on the lamp cover or cap 31, the arrangement being such that the armature circuit 25 can be broken as and when desired by depressing the press-button plunger 36 and thereby separating the pin 33 and strip contact 32.

30 The porous vessel 28 has a transparent lower portion 38 surrounding the filament 39 which is carried in a plug-in holder 40 and connected across battery contact plates 41, 42 insulated 35 from the casing 43, whilst the positive pin of said holder 40 has a spring-loaded plunger 44 associated therewith and making contact with the underside of the plate 1.

With this arrangement if the smaller capacity 45 lamp 5 ceases to function and the larger capacity lamp 6 does not light, this indicates that the filament of one of the lamps has burnt out or 50 the series electric circuit is broken. If on the other hand the larger capacity lamp 6 lights up when the smaller capacity lamp goes out, this 55 indicates that at least the predetermined vacuum has been created in the porous vessel either as a result of the presence of inflammable gas or vapour in the porous vessel 28 or the filament 39 being fused or broken. If upon inspection 60 through the transparent portion 38 or wall of the porous vessel 28, it is found that the filament 39 therein is still glowing or incandescent, and the larger capacity lamp 6 is still alight, this definitely 65 indicates the presence of excess gas or vapour. Under these latter conditions the attendant would operate the switch to break the armature circuit of the relay from time to time, and if the larger capacity lamp 6 does not go out this indicates that an excess of gas or vapour 70 is still present and that the vacuum controlled switch or collapsible diaphragm 24 is still completing the circuit of said larger capacity lamp 6. When the gas or vapour content of the atmosphere falls below the predetermined percentage, the contacts made by the vacuum controlled 75 switch or collapsible diaphragm 24 will break or part but the larger capacity lamp 6 will still function through the action of the relay until the circuit of the latter is again broken, where-

upon the larger capacity lamp 6 will go out and the smaller capacity lamp 5 will again function to indicate that normal or safe conditions now exist. If after repeated operations of the relay circuit switch, the larger capacity lamp 6 remains 5 alight the attendant would clear all men from the danger zone.

It will be evident that the arrangement of the circuit is such that during normal operating conditions with the diaphragm switch open, insufficient current passes through the relay coil to pick up the armature thereof and close the locking circuit. When the lamp 5 is short circuited, however, sufficient current then passes through the relay to operate the switch.

In this latter connection the relay may be adapted to operate further or auxiliary warning lamps, electric bells or the like, of conventional nature, at a distance so as to give indications at one or more points of the presence of excess 20 vapour or gas at the location of the apparatus or porous vessel, said auxiliary means being tapped into the circuit for the lamp 6 in a conventional manner, and operating in accordance with this main warning lamp 6 to show when normal or 25 safe conditions again exist.

It will be seen that apparatus as above described will serve as a reliable indicating means for inflammable vapours or gases in that when any excess of gas or vapours is caused to operate 30 the warning lamp this is maintained on by the relay, and that under these conditions said lamp cannot be put out, by breaking of the relay circuit, until such time as conditions are again 35 normal.

I claim:—

1. An apparatus for indicating the presence of inflammable vapors or gases and of the kind specified, comprising a source of current, an electric signaling or indicating means, including an indicator circuit, two lamps of relatively different capacities arranged in series in said circuit, a relay circuit including a relay, connected to said indicator circuit across the larger capacity lamp, means in said relay circuit including a switch responsive to the presence of inflammable gases, connected across the smaller capacity lamp for completing said relay circuit, means including a holding circuit through said relay to maintain the larger capacity lamp in circuit, irrespective 50 of the subsequent operation of the gas responsive switch, and means to break the holding circuit.

2. An apparatus for indicating the presence of inflammable vapors or gases and of the kind specified, comprising a source of current, an electric signaling or indicating means, including an indicator circuit, two lamps of relatively different capacities arranged in series in said circuit, a relay circuit including a relay, connected to said indicator circuit across the larger capacity lamp, 55 said relay having an armature, means in said relay circuit including a switch responsive to the presence of inflammable gases connected across the smaller capacity lamp for completing said relay circuit, and means to maintain the larger 60 capacity lamp in circuit irrespective of the subsequent operation of the gas responsive switch.

3. An apparatus for indicating the presence of inflammable vapors or gases and of the kind specified, comprising a source of current, an electric signaling or indicating means, including a lamp circuit, a warning lamp in said circuit, a lamp of lower capacity than said warning lamp arranged in series with said warning lamp in said circuit, a relay, the coil of which is in parallel 70 75 80 85 90 95

circuit with said warning lamp, means including a switch responsive to the presence of inflammable gases for completing the circuit through the relay and warning lamp, whereby said relay will be energized when the circuit through the warning lamp is completed by said switch, and means to maintain said warning lamp circuit irrespective of subsequent action or operation of the switch.

5 10 4. An apparatus for indicating the presence of inflammable vapors or gases and of the kind specified, comprising a source of current, an electric signaling or indicating means, including an indicator circuit, two lamps of relatively different capacities arranged in series in said circuit,

a shunt circuit including a relay connected to said indicator circuit across the larger capacity lamp, means in said shunt circuit including a switch responsive to the presence of inflammable gases, connected across the smaller capacity lamp 5 for completing said shunt circuit and effective when closed to complete said shunt circuit to cut out said lamp of smaller capacity and to increase current flow to said lamp of larger capacity, means including a holding circuit through 10 said relay to maintain the larger capacity lamp in circuit, irrespective of subsequent operation of the gas responsive switch in said shunt circuit, and means to break said holding circuit.

HENRY THOMAS RINGROSE. 15
